UNITED STATES PATENT OFFICE.

LEWIS E. WATERMAN, OF ROCKFORD, ILLINOIS, ASSIGNOR TO EMERSON-BRANTINGHAM COMPANY, OF ROCKFORD, ILLINOIS, A CORPORATION OF ILLINOIS.

POTATO DIGGER.

Application filed June 9, 1919. Serial No. 302,660.

To all whom it may concern:

Be it known that I, LEWIS E. WATERMAN, a citizen of the United States, residing at Rockford, in the county of Winnebago and

5 State of Illinois, have invented certain new and useful Improvements in Potato Diggers, of which the following is a specification.

This invention relates to machine potato 10 diggers of the type characterized by an inclined elevator frame having a plow at its forward end, an endless elevator and separator extending upwardly and rearwardly from the plow, and a shaker at the rear of 15 the elevator. The vines, potatoes and dirt are raised by the plow onto the elevator which separates the dirt from the vines and potatoes and delivers the latter onto the shaker, which further separates the vines and 20 potatoes and delivers them separately at the rear of the machine.

In the absence of the use of an independent power unit to drive the elevator and shaker, power is taken from the main 25 supporting wheels for driving these devices. It is desired to disconnect such devices from the driving means when the machine is simply being transported out of operation, and heretofore clutches have been 30 included in the driving means for this purpose. But these driving connections and clutch constructions have been very inconvenient and troublesome to operate, in that it was necessary for the driver to leave his 35 seat on the machine to throw out certain gears or make certain adjustments to discontinue or establish the driving connection. On the other hand, several driving connections have been provided in which a 40 clutch is automatically operated when the plow is raised and lowered; but so far as I am aware, the devices of this character have never been commercially successful, because they have not satisfied certain conditions 45 and requirements inherent in the construction and operation of potato digging machines. In other words, the general practice is to transmit power through a chain and sprocket connection from each driving 50 wheel to the adjacent end of the elevator drive shaft, or to a sprocket wheel meshing directly with the endless elevator. The clutches interposed in these driving connections do not under all conditions have 55 the proper engagement, and consequently

a torsional strain or unequal drive is imposed on the elevator or its immediate driving shaft, which is detrimental to the operation.

The primary object of the present invention is to overcome these objections by the provision of a generally improved potato digger including a novel driving mechanism, which will be automatically engaged and disengaged when the plow is lowered 60 and raised respectively, and will transmit the drive in an entirely practical and satisfactory manner.

Another object is to provide a control in which by operation of a single lever, the 70 driver can simultaneously raise the plow out of the ground to an inoperative position, elevate the rear end of the shaker so that the same shall not be damaged in turning or backing, and disconnect the drive wheels 75 from the elevator and shaker. So far as I am aware, these operations have never been simultaneously performed through the agency of a single operating lever.

Still another object is to support the 80 shaker in a novel manner with the view to giving it a most effective shaker action, this being accomplished in the present instance by the peculiar arrangement of the pendent shaker supporting links.

Other objects and attendant advantages 85 will be appreciated as the invention becomes better understood by reference to the following description when considered in connection with the accompanying drawings, 90 in which—

Figure 1 is a side elevation of a machine potato digger embodying my improvements;

Fig. 2, a plan view of the potato digger; 95
Fig. 3, a longitudinal sectional view taken substantially on the line 3—3 of Fig. 2;

Fig. 4, an enlarged fragmentary sectional view taken substantially on the line 4—4 of Fig. 2;

Figs. 5 and 6, fragmentary sectional views taken substantially on the lines 5—5 and 6—6 respectively, of Fig. 4; and

Fig. 7, a full size detail view taken on the line 7—7 of Fig. 5.

In the present illustration of my improvements, the main frame which will be termed the elevator frame, designated generally by reference character 8, is tiltably supported intermediate its ends on the through axle 9 110

carried by the drive wheels 11. This frame may be of suitable construction, and as shown, consists of longitudinal side sills 12 joined at their forward ends by a plow or shovel structure 13 and at their rear ends by the transverse connecting bar 14 and the elevator drive shaft 15. Each sill 12 is equipped with a bearing bracket 16 in which the axle 9 is journaled. An endless 10 elevating conveyor and separator 17 of suitable link construction, trained over rollers 18 at the forward end of the frame and sprocket wheels 19 fixed to the drive shaft 15, is adapted to be agitated through its upper reach by elliptical idlers 21, or by any 15 other means suitable for the purpose.

The forward end of the main frame is joined to a pole truck or draft frame designated generally by character 22. The side 20 bars of the pole truck are in the form of goose-neck beams 25 pivotally connected at their lower extremities to the forward portion of the main frame at the point 26. By means of a connection operating between the 25 main frame and the pole truck the pivotal point 26 is raised so as to tilt the main frame about the axle 9 to raise the plow 13 from the ground. For this purpose, a rock shaft 27 mounted on the beams 25 of the pole 30 truck, is equipped with crank ends 28 connected to the main frame rearwardly of the pivots 26 by means of the connecting rods 29. A hand lever 31 fixed to the shaft 27 and having the usual latch connection with 35 a notched segment is adapted to be operated forwardly and backwardly to lower and elevate the plow, it being manifest that when the lever is swung rearwardly from the position shown in Fig. 1, the main frame 8 will be tilted in a counter-clockwise direction about the axle, thereby raising the plow to an elevated inoperative position, a contractile spring 32 being employed to assist in this movement.

45 The vines and potatoes after having been elevated by the endless elevator 17 are delivered onto a shaker at the rear of the elevator, which by its riddling action loosens the dirt from the potatoes and also separates the 50 vines therefrom, delivering the potatoes onto the ground at the rear of the machine.

It is desired to raise the rear end of the shaker to an elevated inoperative position when the plow is raised so that when backing 55 the machine or transporting it idly there will be no chance of damaging the tines; and it is further desired to elevate the shaker simultaneously with and by the operation of raising the plow. This is effected by a connection between the shaker-supporting frame 37 and the manually operable shaft 27 at the front of the machine. Such connection consists of a link 54 connected at its rear end to the forward arch 60 39 of the shaker-supporting frame and at

its forward end to a notched segment 55 loosely mounted on the shaft 27 and co-operable with a hand lever 56, also loosely mounted on the shaft. It will be plainly evident that when the plow 13 is raised by 70 swinging the hand lever 31 rearwardly, the pole truck frame and consequently the shaft 27, will be shifted upwardly and forwardly and the rear end of the elevator frame rearwardly and downwardly so that by 75 reason of the relative movement between the shafts 15 and 27 the connecting link 54 will be drawn forward and will swing the shaker-supporting frame 37 in a clockwise direction about the shaft 15, thus elevating the 80 rear end of the tines sufficiently to be out of danger when backing or turning around.

Means are now provided for driving the elevator shaft 15 at both ends from the 85 wheels 11 and in such a manner that the drive may be instantly and equally transmitted to both ends of said shaft simultaneously with lowering the plow into working position, and discontinued upon raising the plow to inoperative position. These 90 means consist of a driving connection between each wheel and the adjacent end of the shaft 15 including a clutch especially designed to meet the conditions present, and a clutch-operating member controlled by movement of the plow into and out of working position. The drive connection at each side of the machine being similar, a description of one will suffice. Referring particularly to Figs. 4 to 7 inclusive, it will be 100 seen that the driving wheel 11 is fixed to a relatively long sleeve bearing 57 loose on the axle and that a casing 58 having an internal toothed ratchet face 59 is fixed to and contiguous with the sleeve 57 and the 105 hub of the drive wheel. A relatively large-diameter driving sprocket 61 loosely revolvable about the axis is, in the present instance, constructed to provide a hub 62 journaled on the sleeve 57, a radial wall 63 closing the open side of the ratchet casing, and annular walls 64 extending laterally from both sides of the central wall or web 63 and serving to prevent the entrance of dust and dirt and other foreign particles to the clutch 115 parts. The driving sprocket 61 carries a pair of diametrically opposed pawls or dogs having a part 65 disposed in the compartment between the casing 58 and the web 63 and engageable with the internal toothed face and a part 66 disposed at the inner side of the web 63 and serving as a tappet adapted to be actuated by an operating part for disengaging the part 65 from said toothed face. The tooth-engaging part 65 of each pawl has a pivot boss 67 (Fig. 7) revolvable in an aperture 68 in the web 63 and a reduced end 69 which receives the part 66; and the swinging end of the part 65 is provided with a boss 71 extending 120

- through an arcuate opening 72 in the web 63. Bolts 73 and 74 passing through the bosses 67 and 71 respectively connect the parts 65 and 66 fixedly together and yet 5 allow these parts to oscillate as a unit about the boss 67. The part 66 is provided with an actuating finger or tappet 75 disposed in substantially right angular relation to the tooth-engaging part 65 and in co-operative 10 relation with an operating member designated generally by character 76 loosely revolvable about an annular bearing 77 formed integral with the fixed bearing 16 which is connected to the frame. The pawls 15 are constantly urged by means of expansion springs 78 into engagement with the toothed face 59 and are adapted to be disengaged therefrom by actuating the tappets 75 through means of the operating member 76. 20 This operating member as shown in Figs. 4 and 5, has an annular operating face 79 of frusto-conical shape and is adapted to be moved lengthwise of the axle to bring its annular surface into contact with the 25 tappets 75 and move the same radially by the inclination of said annular surface, thus disengaging the pawls against the pressure of the springs 78. A simple and effectual way of imparting this longitudinal movement to the operating member 76 is through 30 means of spirally arranged threads or guides 81 formed on the periphery of the bearing 77 and fitting in similar spiral recesses in the member 76. By means of an operating 35 link 82 connected to a depending lug on the member 76, the latter may be oscillated and thereby moved lengthwise of the axle for actuating the pawls. It will be evident that by oscillating the member 76 in a clockwise 40 direction, viewing Fig. 5, this member will be moved outwardly, that is, to the right viewing Fig. 4, and will thereby disengage the pawls and hold them in inoperative position. It will be especially noted that due 45 to the annular surface 79 of the operating member 76, the pawls 65 will be instantly engaged regardless of the position in which the sprocket wheel 61 is standing. Thus when the operating members 76 at both sides 50 of the machine are simultaneously operated both sprocket wheels will be instantly and correspondingly put into operation, and since these sprocket wheels are in direct driving connection with the adjacent ends 55 of the elevator drive shaft 15, it will be manifest that this shaft will be simultaneously and equally driven at both ends. The connection between each drive sprocket 61 and the elevator drive shaft is through the 60 medium of a suitable sprocket chain 83 trained over a sprocket gear fixed to the shaft 15 and over suitable idler gears 84 arranged so that the chain meshes with the drive sprocket 61 only on the lower reach 65 of the chain. The clutch-operating rods 82 reach forwardly and have a yielding connection with the pole truck frame 85 which yielding connection prevents breakage of the clutch parts when the latter are not in immediate position to respond to movement 70 of the pole truck frame. By reason of these connections between the pole truck frame and the clutches the latter will be automatically disengaged when the plow is raised and engaged when the plow is 75 lowered.
- In the operation of my improved potato digger, the operator seated on the machine will lower the plows into the ground by manipulating the hand lever 31, that is, by 80 pressing the lever forwardly to the position shown in Fig. 1. This not only puts the plow in working position in the ground, but as explained above, lowers the shaker to working position and also simultaneously 85 engages both clutches so that the elevator drive shaft 15 will be equally driven from both ends. Upon the reverse movement of this operating lever, the several operative parts will be simultaneously rendered inoperative. Thus the operator by means of a single lever controls all of the operating 90 parts of the machine and by this means is enabled to quickly put the machine into and out of operation. As a consequence, the operator can more quickly, accurately and conveniently handle the machine because less time and attention are required for operating or adjusting the different parts and practically his whole attention can be directed 95 to managing the horses and making the turn properly.
- While I have illustrated and described one practical working embodiment of my improvements, it should be understood that 100 various changes might be made in the construction and arrangement without departing from the spirit and scope of the invention as expressed in the appended claims.
- I claim:
1. In an implement of the character described, the combination of an axle, a pair of driving wheels supporting the axle, a frame supported on the axle and adapted to be tilted thereon, a transverse driven shaft 110 journaled on the frame, a drive member for each drive wheel concentric with and loose on the axle, a direct driving connection between each drive member and the adjacent end of the driven shaft, a clutch concentric 115 with and operable between each drive member and the adjacent drive wheel for connecting and disconnecting said drive member and wheel, and means for automatically operating the clutches by tilting the frame.
  2. In an implement of the character described, the combination of an axle, a pair of drive wheels supporting the axle, a frame supported on the axle and adapted to be tilted thereon, a transverse driven shaft 120

journaled on the frame, a drive member for each drive wheel concentric with and loose on the axle, a direct driving connection between each drive member and adjacent end 5 of the driven shaft, a clutch concentric with and operable between each drive member and the adjacent drive wheel for connecting and disconnecting said drive member and wheel, and a connection between the frame 10 and movable element of each clutch for connecting and disconnecting the latter by tilting the frame.

3. In an implement of the character described, the combination of an axle, a pair 15 of driving wheels supporting the axle, a frame supported on the axle and adapted to be tilted thereon, a transverse driven shaft journaled on the frame, a sprocket wheel fixed to each end of said driven 20 shaft, a driving sprocket for each drive wheel concentric with and loose on the axle, a chain connecting each driving sprocket wheel with the sprocket wheel on the adj-

cent end of the driven shaft, a clutch concentric with and operable between each driving sprocket wheel and the adjacent drive wheel for connecting and disconnecting them, and means for automatically operating the clutches by tilting the frame. 25

4. In an implement of the character described, the combination of an axle, a pair of driving wheels supporting the axle, a frame supported on the axle and adapted to be tilted thereon, a wheel-supported pole truck connected to the forward end of said frame, 30 means operable between said pole truck and frame for tilting the latter, a driven shaft journaled on the frame, means for driving said shaft from one of the driving wheels, including a clutch concentric therewith, and means connected to the pole truck and actuated thereby when tilting said frame for automatically connecting and disconnecting said clutch. 35

LEWIS E. WATERMAN.
